ANTIBACKFLOW VALVE

Everett P. Coon, Boise, Idaho

Application April 6, 1950, Serial No. 154,248

1 Claim. (Cl. 182—25)

1

This invention relates to anti-backflow valves and, more particularly, to a valve for preventing ingress of sewage or tidewater to a building outflow system.

The primary object of this invention is to provide an anti-backwater valve for connection between the sewage outflow pipe, generally in the basement or ground floor of the building, and the main sewage line or branch line, the particular object being to provide such a valve that will conserve the grade in the system. The problem of preventing backflow of sewage or tidal waters from a sewage outflow and related pipes in a building almost invariably occur where there is very little grade between the pipes in the bottom of a building and the main sewage line. When the main sewage line is overlooked or when the tidal or rain waters back up in the main sewer line, there results the obvious tendency for the sewage to back up into the lower parts of the building sewage system, thereby creating untenable conditions in the building but also with a resultant deposit of trash and debris in the building sewage system. Accordingly, it is now intended to provide an anti-backwater valve installable in existing systems without material loss of grade or change in direction of the existing pipes.

Another object of the invention is to provide an anti-backwater valve which, in operation, relies almost entirely on gravity and flotation, respectively, for its opening and closing. Stated conversely, it is proposed now to provide a gravity-opening, flotation-closing ball valve which does not depend in any material respect on the velocity of out-flowing sewage for its opening or, on the other hand, does not depend on velocity of backwater for its closing, the importance of this phase of the invention being appreciable in that sewage systems having backwater problems have relatively little fall and consequently relatively little velocity in the flow of sewage or water in either direction. In contrast with previous attempts to provide a substantially horizontally arranged check valve wherein velocity of flow therethrough invariably played an important part, the object now is to provide a flotation type check valve wherein only the significant opening and closing movements of the ball are in a substantially vertical direction and wherein the other movements of the ball approach the horizontal. By limiting the vertical path of movement of the ball, the vertical dimensioning of the entire valve is thereby held to the minimum.

2

Still another object of the invention is to provide an anti-backflow valve having cleanout facilities arranged immediately over the valve seat so that the valve may be easily inspected and cleaned, and so that any debris forced through manually, or by the automatic washing action of the sewage, falls through the valve away from the valve seat and towards output or side of the valve from whence it will pass without obstruction to the main sewage line.

These and other objects will be apparent from the following specification and drawing in which:

Fig. 1 is a vertical section taken longitudinally through the middle of the valve; and

Fig. 2 is a vertical transverse section taken along the line 2—2 of Fig. 1.

Referring now to the drawing in which like reference numerals denote similar elements, the backwater valve has a hollow casing indicated generally at 2 and preferably cast of suitable metal such as iron. Casing 2 is generally Z-shaped and comprises a horizontal inlet pipe 4 dimensioned for fitting with a sewage pipe usually extending horizontally beneath the basement or ground floor of a building. Preferably, a slight excavation is made to accommodate casing 2 so that it rests in the position shown in Fig. 1 of the drawing. Horizontal inlet pipe 4 terminates in a cylindrical cleanout chamber 6 which is closed at its top by removable closure cap 8 preferably formed of brass, it being obvious that when cap 8 is removed, any debris collecting in chamber 6 may be removed manually or forced downwardly through the valve.

In the bottom of chamber 6 there is formed a relatively large vertical passage 10 surrounded by a flanged recess 12 in which fits an annular valve seat 14, preferably formed of "neoprene" or other plastic material resistant to grease and oil and including on its working face an annular ring seal 16. In the region below valve seat 14, casing 2, on the outlet side of the valve, extends downwardly in the region indicated generally at 17, corresponding to the vertical leg or juncture member of a Z, and thence laterally to terminate in a horizontally extending outlet 18. In the interior of the angle between downwardly and laterally extending portions 17 and 18 there is an enlargement in the top of outlet 18 constituting an ante-chamber 20 having a semi-cylindrical upper wall 21 as best seen in Fig. 2. The interior of ante-chamber 20 is contiguous with the remainder of the interior of the outlet side of the valve, there being a pair of guide ribs 22 oppositely disposed on each side of the lower por-

tion of the ante-chamber. As shown in Fig. 1 guide ribs 22 are inclined upwardly from right to left, the upper portions 22a lying immediately below valve seat 14 being relatively steeply inclined and the lower portions 22b lying below ante-chamber 20 being relatively gradually inclined. It will be observed further that the disposition and inclination of guide ribs 22 correspond with the upper semi-cylindrical wall 21 of ante-chamber 20 so as to loosely to confine a hollow floating ball 26. Ball 26 may be suitably formed of sheet metal or plastic.

Ball 26 is shown in full line position in Fig. 1 seated upwardly against ring seal 16 of valve seat 14, a position it assumes by floating backwardly and upwardly on backwater rising through outlet 18. In the normal operation of the valve, when there is no backwater, ball 26 rolls by gravity down steeply inclined rib portions 22a and thence laterally away on gradually inclined rib portions 22b to its dash line position. It will be observed that in the dash line position of ball 26, the latter lies almost entirely out of the line of normal flow of sewage passing through the valve. However, backwater rising in the outlet side of the valve will reach ball 26 when the latter is in its dash line position long before it rises to the level of seat 14. Thus, in the latter rising movements of the backwater, ball 26 floats upwardly and laterally to its full line position wherein it seats against ring seal 16 so as to prevent any backflow through the valve.

In event a cleanout becomes necessary, closure 8 is lifted from chamber 6 whereupon large debris may be manually removed or forced downwardly passed valve 14. It is noteworthy that any debris forced or washed through valve seat 14 passes on directly to outlet 18. Because of the arrangement of ante chamber 20 contiguous with and above outlet 18, and the disposition of the ribs 22 adjacent the flow path, sewage through which valve tends always to keep ante chamber 20, ribs 22 and ball 26 free of debris or encumbering deposits.

The invention described above is not limited to the structure specifically disclosed, but is in-

tended to cover all modifications, substitutions, and equivalents within the scope of the following claim.

I claim:

5 An anti-backflow valve comprising a hollow casing having a substantially horizontally extending inlet conduit terminating in a cylindrical chamber with substantially coaxial openings through the upper and lower sides thereof and having an outlet conduit extending downwardly and thence laterally from the open lower end of said chamber, a removable cap for the opening in the upper side of said chamber, the lower side of said chamber having an upwardly facing substantially annular shoulder therein surrounding the opening and defining a pocket for receiving a valve seat, an annular valve seat engaged in said pocket, the inner periphery of said valve seat protruding inwardly into the last-named opening, inclined guide ribs extending longitudinally along opposite sides of said outlet conduit, said guide ribs having upper end portions lying substantially beneath said valve seat and lower end portions extending laterally therefrom towards the outlet end of said outlet conduit, and a buoyant valve rollably supported on said ribs, whereby normally said ball valve is assisted by gravity to roll on said ribs but, upon rise of backwater in said outlet conduit, floats 30 upwardly to close against said seat.
